UNITED STATES PATENT OFFICE.

HOWARD S. CRAVER, OF CHICAGO, ILLINOIS, ASSIGNOR OF ONE-HALF TO HENRY S. JUDD, OF CHICAGO, ILLINOIS.

WASHING MACHINE.

1,412,924.

Specification of Letters Patent. Patented Apr. 18, 1922.

Application filed March 21, 1921. Serial No. 454,020.

To all whom it may concern:

Be it known that I, HOWARD S. CRAVER, a citizen of the United States, residing at Chicago, in the county of Cook and State 5 of Illinois, have invented a certain new and useful Improvement in Washing Machines, of which the following is a specification.

My invention relates to washing machines, especially that type in which there are plungers which have a vertical reciprocatory movement and also an intermittent rotary or angular movement. The invention is particularly adapted to the type of machine in which the plungers are operated from a 15 shaft passing up through the bottom of the clothes receptacle. In a machine thus operated from underneath, and with the intermittent rotary movement always occurring in the same direction, the clothes are apt to become wrapped around the center post and become torn. In my prior Patent No. 1,361,228 granted to me December 7, 1920, I have shown a machine which avoids this difficulty, but the rotary movement does not always occur at the same end of the stroke. 20 In my prior machine when the plungers are rotating in one direction the rotary movement occurs when the plungers are up, out of the water, as is proper for that type of machine, but when the plungers are rotating in the other direction, the rotary movement occurs when the plungers are down in the water, or near the lower end of the vertical movement. In the latter case, when 25 the rotary movement occurs, the plungers are in engagement with the clothes and it becomes necessary to overcome the resistance offered by both the clothes and the water. The object of my present invention 30 is to produce a machine which has the advantage of not only reversing the direction of rotation periodically, but also of having the rotary movement always occur near the same end of the stroke; and in the vacuum 35 plunger type, when the plungers are up above the surface of the water. While my present invention is intended primarily for a machine of the vacuum plunger type shown in my aforesaid patent, it is also applicable to a machine of the "dollie" type in which the washing element descends periodically into the water and engages the clothes for agitating and washing them. 40 By taking advantage of the underlying principles of my invention, it becomes possible

to have the intermittent rotary movement of the dollie always occur when the dollie is down in engagement with the clothes.

I obtain my object by the mechanism illustrated in the accompanying drawings in 45 which—

Figure 1 is a side elevation of a machine of the vacuum plunger type showing the clothes receptacle in vertical section.

Figure 2 is a top plan view of the ratchet 50 mechanism which produces the intermittent rotary movement of the type of machine shown in Figure 1.

Figure 3 is a front elevation of the parts shown in Figure 2. 70

Figure 4 is a view looking towards the left in Fig. 3.

Figure 5 is a vertical section on the line 5—5 of Figure 2.

Figure 6 is a vertical section on the line 75 6—6 of Figure 2.

Figure 7 is a vertical section of a machine employing the "dollie" type of washing element. In this case the intermittent rotary movement always occurs when the dollie is 80 near the lower end of its stroke instead of at the upper end of the stroke as in the form shown in Figure 1.

Figure 8 is a top plan view of the ratchet mechanism which produces the intermittent 85 rotary movement of the type of machine shown in Figure 7.

Figure 9 is a front elevation of the parts shown in Figure 8.

Like numerals denote like parts throughout the several views. 90

Referring first to the form shown in Figures 1 to 6 inclusive, the clothes receptacle 1 is mounted upon a frame 2 of any suitable construction. Passing up through the bottom of the receptacle is a hollow post 3 which forms a guide for the vertically reciprocating and intermittently rotating shaft 4. This may be referred to as the "pounder shaft." Fastened to the top of the shaft 95 100 is a yoke 5 provided at its ends with vertically arranged rods 6 which fit slidably within sleeves 7 provided at their lower end with plungers 8. By preference the connection between rods 6 and sleeve 7 is resilient 105 to permit slight upward yielding of the plungers in case they meet unusual resistance from the clothes. Thus far the construction is known.

Referring now to the mechanism which 110

produces the reciprocatory movement of the main shaft 4 in a vertical direction:

A lever 10 is mounted upon a stationary pivot 12 in the frame-work 2 as shown in the lower left portion of Figure 1. Suitable means are provided for imparting to this lever a constant swinging movement back and forth in a vertical plane. The means illustrated comprises a link 14 connected to a crank 16 on a gear wheel 17 connected with a pinion 18 fastened to a sheave 19 driven by a belt 20 from a motor 22.

At its free end lever 10 is connected by a link 25 to a pin 26 carried at the lower end of a yoke 28 swiveled to the lower end of shaft 4 as shown in detail in Figures 4 and 6. The yoke has a sleeve portion 29 which encircles the lower end of the shaft above integral collar 30 formed at the lower end of the shaft. The construction is such that the vertical movement of lever 10 causes a corresponding vertical movement of the main shaft 4, but said shaft is rotatable independently of the lever and interconnecting parts.

Referring now to the mechanism which produces the intermittent rotary movement of the main shaft and plunger, first in one direction and then, after a series of movements, in the opposite direction:

An arm 36 is rigidly fastened to lever 10 near the free end thereof. The outer end of this arm is connected by a pivot pin 37 to a slotted link 38. A slot 40 is formed in link 38 at the end opposite to pivot 37. Passing through this slot is a pin 41 best shown in Figures 3 and 5. Pin 41 is fastened to a pawl carrier 42 which oscillates about a vertical stud 44. Pin 41 fits loosely in slot 40 and hence it is evident that link 38 will have a certain amount of lost motion relatively to the pin. The amount of this lost motion is regulated by a block 46 best shown in Figures 2 and 3. This block is slidable in slot 40 and its position lengthwise of the link is regulated by an adjusting screw 47 which is swiveled to the block and works in an internally threaded cross arm 48 formed in the link. The screw is provided with a knurled head 50 by which it may be rotated to thus control the position of the block in the link. When the link moves forward (towards the left Figs. 2 and 3) the block engages the depending portion of the pawl carrier 42 and advances it angularly about the stud 44 as an axis. The return movement of the pawl carrier is effected normally by the tension spring 52 which is anchored to the stud 54, although the return of the pawl carrier is assured by reason of the closed outer end of link 38 which is adapted to engage the pin 41 as the link moves towards the right, Figures 2 and 3. A stop pin 55 mounted in

the plate 63, hereinafter mentioned, limits the distance which the pawl carrier may move under the influence of spring 52 hereinafter referred to.

Pawl carrier 42 has a horizontal socket 56 formed in it as best shown in Figures 2, 4 and 5. A pawl 57 fits slidably in this socket and is backed up by a compression spring 58. This pawl is prevented from rotating by means of a pin 60 which overrides a flattened portion 61 of the pawl. The pawl engages the teeth of a gear wheel 62 which rests upon a non-rotary plate 63 and is rotatable about stud 44 as an axis. According to the design shown the pawl drives the gear wheel always in a clockwise direction when viewed from the top as in Figure 2. When the pawl moves toward the right, Figure 2, it clicks over the gear wheel and imparts no motion to it. For identification wheel 62 may be termed the "master gear wheel" to distinguish it from the pinion 64 and intermediate gear wheel 66, which also bear upon plate 63. Pinion 64 is pinned to the main shaft 4 for rotating it. The intermediate gear 66 meshes with the pinion at all times, and rotates about the stud 54 as an axis.

The gear wheels 62, 64 and 66 are mutilated in such manner that while the master gear always rotates in the same direction, the pinion will rotate part of the time in one direction and part of the time in the opposite direction. This is accomplished by forming each of the gear wheels in two sections, an upper and a lower. The lower section of gears 62 and 66 are toothed throughout their entire circumferences so that they are always in mesh with each other and will rotate equal amounts in opposite directions. The lower section of the pinion is toothless while the upper section is toothed throughout its circumference. The upper section of the master gear 62 is toothless throughout something more than one-half of its circumference and toothed throughout the remaining portion, and the same is true of the intermediate gear 66, the result being that they engage the pinion alternately and rotate it first in one direction and then in the other.

Gear 66 is prevented from rotating backwark (clockwise, Figure 2) by a backstop pawl 70. Said pawl is pivoted upon a pin 71 fastened to plate 63 and is urged toward the gear by a spring 72. It is desirable in order to prevent accidental rotation of pinion 64 to provide a double click pin 74 which is slidably mounted within a block 76 and pressed towards the pinion by a spring 77 as best shown at the upper portion of Figure 2.

In operation, as the lever 10 oscillates up and down under the action of the link 14 and other parts of the driving mechanism

it causes link 25 to move the main shaft or pounder shaft 4 up and down in the well known manner. The swing of the lever and arm 36 causes the pin 37 to travel back and forth along an arc centered at the pin 12 and the horizontal component or rise of this arc produces a horizontal as well as a vertical movement of the pin and a corresponding reciprocatory movement of the link 38 approximately in the direction of its length. This movement of the link produces an oscillatory movement of the pawl carrier 42 about the stud 44 as an axis, thus imparting to the gear 62 an intermittent rotary movement in a clockwise direction when viewed from above as in Figure 2. The parts are so constructed and arranged that the block 46 does not engage the pawl carrier 42 until near the end of the upstroke of the vertically reciprocating parts and the result is that the rotary movement of the plungers does not occur until they are nearing the upper end of their travel, at which time they are above the ordinary water level in the clothes receptacle. The consequence is that their rotary movement occurs always when there is nothing to obstruct or retard their rotary movement, and never when they are down in engagement with the clothes, or even in the water. The throw of the pawl carrier 42 may be increased by adjusting the block 46 closer towards it and decreased by adjusting the block further away from it. Of course, the greater the throw of the pawl carrier the greater will be the amount of angular movement of the plungers each time the pawl moves forward. If the block is moved closer toward the pawl carrier and the angular movement thus increased, the angular movement will commence earlier in the upstroke and this might be carried to a point where the angular movement starts before the plungers actually leave the water, but this will ordinarily not be the case.

Now referring to the type shown in Figures 7 to 9 inclusive. Fundamentally the only difference is that instead of vacuum plungers 8, a so-called "dollie" 80 is employed at the top of the pounder shaft 4, said dollie having prongs or fingers 82 adapted to plunge down into the clothes, intermittently, and impart to them a short angular or rotary movement for agitating them and thus producing a washing action. This makes it desirable if not necessary to have the rotary movement always occur at the lower end of the stroke, and as a result of my invention it becomes possible to effect it. This action is accomplished basically by facing the pawl 57 in the opposite direction from the one shown in Figure 2, the purpose being to advance the gear 62 at a time when the pawl carrier 42 is moving toward the right, as viewed in the

drawings. In this case the pawl carrier is attached to the spring 52 by means of a lug 84 which is on the opposite side of stud 44 from the pawl. A stationary pin 86 mounted on plate 63 limits the movement of the pawl carrier under the influence of spring 52. In this case also, the adjusting means on the slotted link is placed on the opposite side of the depending portion of the pawl carrier as will now be explained. Link 38^a which is analogous to link 38, is provided with a sliding block 90 in addition to the block 46 previously described. Block 90 is on the opposite side of arm 42 and is controlled by an adjusting screw 92 which is swiveled to the block and works in the internally threaded outer end 94 of the link. The screw is provided with a knurled head 95 for rotating it and thus controlling the position of the block in the link.

In operation, the action of the mechanism is the same as before except that the block 46 will usually not be called on to operate and will be backed off out of the way of pawl carrier 42. Said pawl carrier, however, will be acted upon by the block 90 as the latter moves toward the right, and the degree of lost motion will depend upon the amount of motion of the block toward the left after the pawl carrier has been arrested in its leftward movement by the stop pin 86. As the movement of the pawl carrier to the right will always occur when the pounder shaft 4 is near the bottom of its stroke, it follows that the rotary movement of the dollie will also occur always near the bottom of the stroke and thus impart a downward and a rotary movement to the clothes. The shaft periodically reverses so that the intermittent rotary movements occur first in one direction and then in the other. By preference a plurality of such movements occur in one direction before the reversal takes place, and the present design operates in this manner.

It will thus be seen that in both cases the action is the same except that in one case all of the rotary movements occur near the top of the stroke and in the other case they all occur near the bottom.

Having thus described my invention, what I claim as new and desire to secure by Letters Patent is:

1. In a washing machine in which the washing element has an intermittent rotary movement and a vertical stroke, means for periodically reversing the direction of rotation after a plurality of rotary movements have occurred in the same direction, said means being operative always near the same end of the stroke, and nonoperative elsewhere.

2. In a gearing for washing machines, a support, a vertical shaft, means for impart-

- ing to said shaft a vertical reciprocatory movement, means operative near one end only of the travel of said shaft for imparting an intermittent rotary movement to it in one direction, and means operative near the same end of the travel of said shaft for periodically reversing it after the occurrence of a plurality of angular movements in the original direction.
- 5 10. 3. A washing machine having a reciprocatory shaft, means for imparting a plurality of intermittent angular movements to the shaft in one direction, means for periodically reversing the action of said means, and mechanism for confining the action of the first mentioned means to a region near a given end of the reciprocatory movement of said shaft.
- 15 4. A washing machine having a vertical pounder shaft, means for reciprocating it vertically, means for imparting a plurality of intermittent angular movements to said shaft first in one direction and then in the opposite direction, and means for confining all angular movements to a zone located near the upper end of the vertical movement of said shaft.
- 20 5. In a gearing for washing machines, a support, a vertical shaft mounted in said support, means for reciprocating the shaft vertically, and ratchet mechanism for imparting a series of angular movements to the shaft in one direction and then a series in the opposite direction, said ratchet mechanism including a vibrating element, operating in unison with the reciprocatory movement of the shaft, a ratchet actuated by the throw of said vibrating element, and mutilated gears one of which is actuated by said ratchet, always in the same direction, and another of which is fastened to the shaft for rotating it.
- 25 6. In a washing machine, a main shaft arranged vertically, a power device, means connected to said power device for reciprocating the shaft vertically, mutilated gearing geared to said shaft for rotating it in-
- 30 35 40 45 50 55 60 65 70 75 80 85 90 95 intermittently first in one direction for a series of movements and then in the opposite direction, one of the wheels of said gearing constituting a master gear, a ratchet adapted to intermittently rotate said master gear always in the same direction, and means connected to said power device for reciprocating said ratchet.
7. A washing machine having a vertical main shaft, a power device, means connected to said power device for reciprocating the shaft vertically, mutilated gearing geared to said shaft for rotating it intermittently first in one direction for a series of movements and then in the opposite direction, one of the wheels of said gearing constituting a master gear, a ratchet adapted to intermittently rotate said master gear always in the same direction, an oscillatable ratchet carrier, and a lost motion device actuated by the power device for oscillating said ratchet carrier.
8. Mechanism of the class described having a vertical shaft, a power device, means connected to said power device for reciprocating the shaft vertically, mutilated gearing geared to said shaft for rotating it intermittently first in one direction for a series of movements and then in the opposite direction, one of the wheels of said gearing constituting a master gear, a ratchet adapted to intermittently rotate said master gear always in the same direction, a ratchet carrier adapted to move forward and backward for actuating the ratchet, a link operated by the power device and adapted to reciprocate approximately longitudinally for actuating the ratchet carrier, there being lost motion between the link and the ratchet carrier, and an adjustable element on said link adapted to engage the ratchet carrier earlier or later in the travel of the link for thereby regulating the amount of lost motion between the link and the ratchet carrier.

In witness whereof, I have hereunto subscribed my name.

HOWARD S. CRAVER.
